(57) **CLAIM**

We claim the ornamental design for a digital camera, as shown and described.

DESCRIPTION

FIG. 1 is a front, top, right-side perspective of a digital camera according to the present invention with the flash closed and the zoom lens retracted;

FIG. 2 is a back, bottom, left-side perspective thereof with the flash closed and the zoom lens retracted;

FIG. 3 is a front view thereof with the flash closed and the zoom lens retracted;

FIG. 4 is a rear view thereof with the flash closed and the zoom lens retracted;

FIG. 5. is a top view thereof with the flash closed and the zoom lens retracted;

FIG. 6 is a bottom view thereof with the flash closed and the zoom lens retracted;

FIG. 7 is a right-side view thereof with the flash closed and the zoom lens retracted;

FIG. 8 is a left-side view thereof with the flash closed and the zoom lens retracted; and,

FIG. 9 is a front, top, right-side perspective thereof with the flash open and the zoom lens extended.
